FOREIGN PATENT DOCUMENTS

GB 2 230 505 10/1990

Primary Examiner—Stella M Reid*Assistant Examiner*—Elizabeth J Oswecki(74) *Attorney, Agent, or Firm*—Oblon, Spivak, McClelland, Maier & Neustadt, L.L.P.(57) **CLAIM**

The ornamental design for a bottle, as shown and described.

DESCRIPTION

FIG. 1 is a front, top, and right side perspective view of a bottle;

FIG. 2 is a front elevational view thereof, the rear elevational view being a mirror image of the elevational view shown;

FIG. 3 is a right side elevational view thereof, the left side elevational view being a mirror image of the elevational view shown;

FIG. 4 is a top plan view thereof; and,

FIG. 5 is a bottom plan view thereof.

The broken lines in the drawings depict environmental subject matter only and form no part of the claimed design.
